ABSTRACT

A pasteboard shipping container is provided for a tray, the tray being of the type having particular utility in the handling of mail, and the container serving as a carton for enabling the tray to be shipped by air, rail, or other means. The pasteboard container of the invention has the ability of being sealed so as to prevent access by unauthorized persons to the mail loaded in the tray contained in the container, and of being folded flat when not in use. The container of the invention is non-adhesively sealed at both ends after the tray has been inserted in it, to prevent access, and yet to permit the container to be reusable. The container may be made up easily and quickly to receive the tray, without any need for extraneous tools.

1 Claim, 2 Drawing Figures

FIG. 1

FIG. 2

SHIPPING CONTAINER

BACKGROUND OF THE INVENTION

The container of the invention has particular utility for use in conjunction with the corrugated tray described in copending application Ser. No. 447,821 filed Mar. 4, 1974 in the name of the present inventor. As described in the copending application, the corrugated tray has utility in carrying mail from a main post office to sub-station post offices, and for the shipment of mail by air, or by other means. As noted above, the container of the present invention provides a convenient shipping carton for such a tray.

BRIEF DESCRIPTION OF THE DRAWINGS

FIG. 1 is a perspective representation of the corrugated tray described in the copending application; and

FIG. 2 is a perspective representation of the pasteboard shipping container of the present invention, in one of its embodiments.

DETAILED DESCRIPTION OF THE ILLUSTRATED EMBODIMENTS

The tray shown in FIG. 1 is designated 10, and it has a rectangular configuration, as shown. The tray 10 may be constructed as mentioned above, in the manner described in the copending application. The tray 10 has the feature in that it may be formed of pasteboard, or similar material, and it is constructed so that its sides may be held rigid in an upright position without the need for adhesives, or for any other reinforcing means.

When the tray 10 is loaded with mail, and is to be shipped by air, or by other means, it may be enclosed by the pasteboard shipping container of the present invention, so that the contents of the tray may be held intact, and so that pilfering may be prevented.

As shown in FIG. 2, the shipping container 12 of the invention has a generally rectangular shape. The container 12 is formed of corrugated pasteboard, or other appropriate material. The container folds flat when not in use, and it makes up readily and quickly to the configuration shown in FIG. 2, without the need for tools. When the container is squared up to the illustrated position of FIG. 2, the left-hand end in FIG. 2 is closed, by turning up an end flap 14, and by turning in two end flaps, such as the end flap 16. A further flap 18 is formed integral with the outer edge of the end flap 14, and it is folded into a slot 20 in the upper wall of the container 12.

The tray 10, loaded with mail or other material, is then slipped through the right-hand end of the container 12, and past the end portion 18a of the flap 18, which protrudes down into the interior of the container through the slot 20. The tray causes the end portion 18a to be folded back into the position shown by the dotted lines in FIG. 2, so that it is essentially parallel to the outer portion of the flap.

When the end portion 18a of the flap 18 is bent back to its parallel position, there is no way in which the left-hand end of the shipping container can be opened,

without physically tearing the corrugated material. However, when the tray 10 is removed, the flap 18 can again be pulled out of the slot 20, and the container can be again folded flat for reuse.

When the tray 10 is fully inserted in the shipping container 12, a pair of side flaps 22 and 24 can be turned in across the right-hand end, and an upper flap 26 can be turned down to enclose the end. A further bottom flap 28 can be turned over the flap 26, and the flaps 28 and 26 can be sealed to one another by usual railroad seals, which can be inserted through appropriate holes in the flaps, such as the hole 30, so that the right-hand end of the shipping container also may be tamper proof.

15 The invention provides, therefore, a relatively simple and inexpensive shipping container constructed of pasteboard, or the like, and which serves as a convenient shipping carton for mail trays, or the like. The container of the invention has the feature in that both its ends may be appropriately non-adhesively sealed to prevent tampering, and yet the container may be readily reusable. The container also has the feature of being capable of being folded flat when not in use to facilitate storage and shipment of the container itself.

25 While a particular embodiment of the invention has been shown and described, modifications may be made. It is intended in the claims to cover the modifications which come within the true spirit and scope of the invention.

30 What is claimed is:

1. A rectangular shipping container for a tray, or the like, formed of pasteboard, or the like, comprising: spaced and parallel top and bottom panels, and spaced and parallel side panels formed integral with the top and bottom panels, the top panel having a transverse slot adjacent one end thereof; an upturned end flap formed integral with the one end edge of the bottom panel to enclose said one end edge of the container; a first pair of side flaps integral with the side edges of said end flap and turned inwardly into said one end of the container when said end flap encloses said one end of the container; a tab integral with the upper edge of the end flap extending across the outer surface of the top panel and into the slot therein, the end portion of the tab extending through the slot into the interior of the container to be folded back against the inner surface by the action of a tray sliding past the inwardly projecting end of the tab, thereby sealing said one end of the container as long as the tray remains therein and unsealing said one end of said container when the tray is removed; a second pair of side flaps integral with the other end edge of the container to extend across the other end of the container; a further end flap formed integral with the other end edge of the container to be turned over the side flaps of the second pair and enclose said other end of the container; a bottom flap integral with the other end edge of the container to be turned up over said further end flap and to be sealed to said further end flap; and seal-receiving means attached to said further end flap.
